UNITED STATES PATENT OFFICE.

HENRY G. THOMPSON, OF CLEVELAND, OHIO.

PRESSED-METAL HOOK AND METHOD OF MAKING THE SAME.

Application filed May 31, 1922. Serial No. 565,004.

To all whom it may concern:

Be it known that I, HENRY G. THOMPSON, a citizen of the United States, residing at Cleveland, in the county of Cuyahoga and State of Ohio, have invented a certain new and useful Improvement in Pressed-Metal Hooks and Methods of Making the Same, of which the following is a full, clear, and exact description.

10 The present invention relates to a pressed metal article which comprises a base or fastening part and a hook or angularly extending part, and in the instance shown there are two hooks. The use of the article 15 having one hook will fit the article for use in certain instances, and with two hooks will enable it to be used for other purposes, as for instance, the holding of ropes by which awnings, flags, etc., are raised and 20 held in position.

The object of the invention is to produce an article of the character and kind from a blank of sheet metal, bending the same by certain operations performed in dies, and 25 finally producing an article which is better than a cast article, and can be produced at a lower cost of manufacture.

Reference should be had to the accompanying drawings forming a part of this 30 specification, in which Fig. 1 is a plan view of a blank made from sheet metal; Fig. 2 is an elevation of the blank in partly formed condition; Fig. 3 is an end view of the partially formed blank shown in Fig. 2; Fig. 35 4 is a section on the line 4-4 of Fig. 2; Fig. 5 is a bottom plan view of the partly formed blank shown in Fig. 2; Fig. 6 is an elevation with portions in section of the completed article; Fig. 7 is a section 40 on the line 7-7 of Fig. 6; Fig. 8 is a bottom plan view of the article shown in Fig. 6; Fig. 9 is a top plan view of the article shown in Fig. 6; Fig. 10 is an elevation with portions in section of a modified form; and Fig. 11 is a bottom plan view 45 of the device shown in Fig. 10.

In making the article a blank is formed which has what may be termed a central portion 1, an extending arm 2, and optionally, an oppositely extending arm 3. The blank as formed has the arms 2 tapering at the end as suggested at 2^a and 3^a, and at points adjacent to the base the blank is made to extend into pointed portions 2^b, 2^c, 50 3^b, 3^c. Simultaneously the blank is punched

to provide openings, such as indicated at 4, which serve to receive screws. The blank in the condition which has been indicated is perfectly flat.

In the next operation in forming the article the same is bent upon a longitudinal axis so that the arms 2 and 3 are formed into a U-shape, such for instance as indicated in Fig. 4. These arms at their end portion are brought closer together than they are further back, and this is illustrated by reference to Fig. 3, which is an end elevation of the partially formed article shown in Fig. 2. It will be noted that the end of the arm 2 which is represented at 3^x is narrower than that portion of the arm which is represented by 3^y.

At the same time that these arms 2 and 3 are formed into the U shape suggested, they are bent up with respect to the central portion 1 of the blank, assuming a curved direction with respect to the central portion 1. This central portion 1 in the bending of the arms is provided with downwardly extending flanges such as indicated at 1^a and 1^b, which flanges extend along the sides and merge with what may be termed the side members of the U shape which is given to the arms.

In this same operation the holes 4 are 55 countersunk, which appears in Fig. 5, but more clearly appears in Figs. 6 and 7, which figures, however, show the article in finished form.

After the article has been formed up, as 60 shown in Fig. 5, the sides or skirts of the U-shaped portion are still spread apart and the pointed portions 2^b, 2^c, 3^b, 3^c, are spread apart.

In the next operation the flanges of the 65 arms 2 and 3 are bent over and brought together, while the points 3^b, 3^c, and the points 2^b, 2^c, are also rolled over and brought into contact. This produces the finished article 70 which on the under side has the appearance which is shown in Fig. 8. By the method which has been described the arms 2 and 3 are given a substantial tubular shape, while the central portion 1 has a depending flange 75 at the sides thereof, and by the bending in of the points 2^b, 2^c, and 3^b, 3^c, this flange is merged into the ends of the arms. Therefore the reverse side of the article presents a perfectly flat marginal edge, which edge 80 lies all in the same plane, so that when the 85

device is fastened to a wall or board there is no tipping of the device, and additionally it will be noted that the flange on the reverse side of the central portion 1 forms a box-like structure which is without a cover and permits the passage of screws or other fastening implements through the central portion, and into the wood or other substance which is to support the article in question.

In order to strengthen the central portion 1 a bead may be formed in the upper portion, or the part which is between the outwardly extending arms 2 and 3, which bead is represented at 1^b in Fig. 8.

In Fig. 10 there is shown a slightly modified form, and this form is to provide for the use of a single hole, such as indicated at 4^a in Figs. 10 and 11, instead of the two holes which are shown in the other figures. When a single hole is used it is desirable to provide some means for preventing the article turning about the screw or nail, and for this purpose the blank is formed to have one or more extending points 5, these being formed when the blank is formed. Otherwise, the blank and the formation of the article is precisely the same as that which has been described.

When the article as shown in Figs. 10 and 11 is used the points 5 will gouge into the material to which the device is fastened, so that when the screw or nail or other fastening device is inserted through the opening 4^a and tightened, the device will not only be held to its mounting, but will likewise be prevented from turning about the same.

Having described my invention, I claim:—

1. The method of forming a hook-like article which comprises blanking out of sheet metal a blank having a central portion and an extending arm, the central portion of the blank being wider than the arm, forming said blank by moving the edges of the arm portion toward each other to assume a U-shape, and simultaneously moving the marginal parts of the central portion to form flanges for the central portion which are continuous with the sides of the arm, and subsequently rolling over the edges of the U-shaped arm into substantial contact thereby forming a hollow tubular arm and a flanged central portion.

2. The method of forming a hook-like article which comprises blanking out of sheet metal a blank having a central portion and an extending arm, the central portion of the blank being wider than the arm, and said blank being provided with oppositely disposed outwardly extending peaks which are at the junction of the arm portion and central portion of the blank, forming said blank by moving the edges of the arm portion toward each other to assume a U-shape,

and simultaneously forming flanges at the side margins of the central portion, the said peak portions of the blank being simultaneously bent in the general direction of the flanges on the central portion, and subsequently rolling over the edge of the U-shaped arm portion into substantial contact thereby forming a hollow tubular arm and also moving the peaked portions of the blank into contact thereby completing the arm and forming a continuation of the side flanges of the central portion around the ends thereof.

3. The method of forming a hook-like article which comprises blanking out of sheet metal a blank having a central portion and oppositely extending arms, the central portion being wider than the arms, forming said blank by moving the edges of the arms toward each other to assume a U-shape in cross-section and simultaneously bending the marginal parts of the central portion to form flanges continuous with the sides of the arms, and subsequently rolling over the edges of the U-shaped arms into substantial contact on the inner side thereof from the outer ends to the base thereby forming hollow tubular arms and a continuous supporting edge around the central portion.

4. The method of forming a hook-like article which comprises blanking out of sheet metal a blank having a central portion and an extending arm, the said blank portion being wider than the arm portion and the end of the arm being formed tapering, forming said blank by moving the edges of the arm toward each other to assume a U-shape in cross-section, and forming the marginal parts of the central portion to form depending base flanges continuous with the sides of the arm, the width of said arm varying between the end thereof and the part which is attached to the central portion, and subsequently rolling over the edges of the U-shaped arm into substantial contact throughout the length thereof on the inner side thereby forming a hollow tubular arm of slightly varying diameter merging at its lower ends into the base flanges.

5. The method of forming a hook-like article which comprises blanking out of sheet metal a blank having a central portion and an extending arm, the central portion of the blank being wider than the arm and the end of the arm being slightly tapering, forming said blank by moving the edges of the arm portion toward each other to assume a U-shape in cross-section, the width between the marginal edges of the arm varying between the end and the part thereof where it is attached to the central portion, and simultaneously forming marginal parts of the central portion to form opposite parallel flanges continuous with the sides of the arm, forming the said arm with a gradual curve away from the central portion and out of

the plane of said central portion, subsequently rolling over the edges of the U-shaped arm into substantial contact on the under side thereof from the outer end to the base thereby forming a hollow tubular arm of slightly varying diameter and a base having a continuous supporting edge.

6. As an article of manufacture, a device of the character described made of sheet metal, comprising a base portion having in-turned side flanges and an integral tubular arm extending from said base portion, the flanges on the base portion merging into the tubular arm, said arm being curved away from the plane of the base.

7. As an article of manufacture, a device of the character described made of sheet metal, comprising a base portion having in-turned side flanges and an integral tubular arm extending from said base portion, the flanges on the base portion merging into the tubular arm, said arm being curved away from the plane of the base, said base member having an opening through the same for attaching purposes.

8. As an article of manufacture, a device of the character described made of sheet metal, comprising a base portion having in-turned side flanges and an integral tubular arm extending from said base portion, the flanges on the base portion merging into the tubular arm, said arm being curved away from the plane of the base, said base member having an opening through the same for attaching purposes, said base portion being provided with a pointed extension thereby to prevent rotation of the device when the same is secured.

9. As an article of manufacture, a device of the character described made of sheet metal comprising a base portion having in-turned side flanges and integral tubular arms curved away from the plane of the base on the side opposite the flanges of said base, the

flanges on the base portion merging into the 45 tubular arms.

10. As an article of manufacture, a device of the character described made of sheet metal comprising a base portion with in-turned side flanges and an integral tubular 50 arm extending from an end of the base portion and inclined outwardly at an oblique angle therefrom, the metal of said arm having edges abutting along the inner side thereof and the side flanges of the base portion being curved inwardly at the end and merging into said tubular portion.

11. As an article of manufacture, a device of the character described made of sheet metal comprising a base portion with in-turned side flanges and integral tubular arms 60 extending outwardly from the opposite ends of the base portion, the flanges of the base curving inwardly and merging into the tubular arms to provide a continuous supporting edge around the ends of the base portion in the plane of the edges of the side flanges, the metal of the arms having meeting edges 65 extending from the supporting edge of the base at the ends thereof to the outer ends 70 of the arms.

12. As an article of manufacture, a device of the character described made of sheet metal comprising a base portion with in-turned side flanges and outwardly curved 75 tubular arms extending from opposite ends of the base at an oblique angle with respect thereto, the metal of said arms having meeting edges along the inner sides thereof from the base to the outer ends thereof, and the 80 said side flanges being bent inwardly at the ends of the base and merging into the arms to provide a continuous supporting edge around the ends of the base portion.

In testimony whereof, I hereunto affix my 85 signature.

HENRY G. THOMPSON.
